UNITED STATES PATENT OFFICE

2,542,211

AUTOMOBILE LIGHT CONTROL

Guillermo E. Sauri, Mexico City, Mexico

Application February 8, 1949, Serial No. 75,161

1 Claim. (Cl. 200—152)

1

This invention relates to motor vehicle head-light controlling means designed for illuminating the road surface in the direction of travel of motor vehicles around curves, the switches controlling the circuits to the auxiliary lights of the system, being of the mercury type and controlled by the centrifugal force of the vehicle negotiating a curve in the road.

Another object of the invention is to provide an adjustable switch which may be adjusted for operation to compensate for rough and irregular road surfaces which might otherwise cause the operation of the switches to illuminate the auxiliary lamps.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

Referring to the drawing:

Figure 1 is a fragmental plan view illustrating auxiliary head lamps which are controlled by the system forming the subject matter of the present invention.

Fig. 2 is a diagram of the wiring system.

Fig. 3 is an enlarged plan view of the switch housing with the cover removed.

Fig. 4 is a side elevational view of the switch and housing, with one of the side members of the switch housing removed.

Referring to the drawing in detail, the reference character 5 indicates the switch housing in which the tubes 6 and 7, forming a part of the mercury switches, are mounted. These tubes 6 and 7 are secured at their inner ends by means of the clip 8, which is secured to the bottom 9 of the housing 5.

The clip 8 is formed with sockets that receive the inner ends of the tubes 6 and 7 to permit the tubes to move vertically and pivot within the clip 8.

Clips 11 are positioned around the tubes 6 and 7 and are disposed adjacent to the outer ends of the device, the clips being connected with the adjusting screws 12 that extend through threaded openings in the bottom 9, with the result that as these adjusting screws are rotated, the normal angular position of the tubes 6 and 7, with respect to the bottom 9, may be regulated.

The reference characters 13 and 14 indicate auxiliary head lamps which are mounted in any

2

desirable location at the front of the vehicle, the lamp 13 being in circuit with the terminals 15 in one end of the switch housing 5, which in turn are in circuit with contacts in the outer end of the tube 6, through the wires 16 and wire 17, providing a circuit to the lamp 13. The reference character 18 indicates the ground wire of the circuit. The wire 19 that connects with the lamp 14 is in circuit with the terminals 20 in the opposite end of the switch housing, the terminals 20 being in circuit with contact points in the outer end of the tube 7, through the wires 21. The wire 22 provides a circuit from the source of electricity supply 23 to the contacts of the tubes 6 and 7, there being provided a switch 24 in the circuit controlling the circuit. The ground wire from the battery is indicated by the numeral 25, while the ground wire from the lamp 14 is indicated by the reference character 26.

20 The switch housing may be mounted in any desirable place on the vehicle, preferably where the vehicle is level under normal conditions, so that the mercury in the tubes 6 and 7 will normally lie in the position as shown by Fig. 4 of the drawing.

25 It follows that a motor vehicle equipped with the control mechanism forming the subject matter of the present invention, will by the centrifugal force caused when making a turn in the road to the right, throw the mercury in the tube 6 outwardly, completing the circuit to lamp 13, illuminating the road surface in the direction of travel of the vehicle, which is to the right.

When the vehicle has made the turn and assumes a level position on the street or road surface, the mercury in the tubes 6 and 7 will by gravity, assume the position shown by Fig. 4, breaking the circuit, the auxiliary light being cut out.

40 If the motor vehicle negotiates a curve to the left, the centrifugal force caused by the vehicle making the turn, will throw the mercury in tube 7 outwardly, completing the electric circuit to light the lamp 14, illuminating the road surface at the curve directly in the path of travel of the vehicle.

Should it be desired to operate the vehicle over an exceptionally rough road, it may be desirable to adjust the outer ends of the device by elevating them so that the jarring and movement of the vehicle passing over the irregular surface will not cause the mercury in the tubes 6 and 7 to move to complete the circuits to the auxiliary lamps while the vehicle is moving over a straight way section of the road.

Having thus described the invention, what is claimed is:

A mercury control switch comprising a switch housing having a bottom member, a clip secured centrally of the bottom member, inclined mercury switch tubes, the inner ends of said mercury tubes being pivotally held within the clip, clips secured around said tubes adjacent to the outer ends thereof, adjusting screws operating through openings in the bottom member, connected with the clips at the outer ends of the tubes, whereby the outer ends of said tubes are adjusted vertically, regulating the operation of the tubes and switch.

GUILLERMO E. SAURI.
